SEPARATION OF MIXTURES OF HYDROCARBONS

Melvin A. Dietrich, Wilmington, Del., assignor to
E. I. du Pont de Nemours & Company, Wil-
mington, Del., a corporation of Delaware

No Drawing. Application May 19, 1936,
Serial No. 80,556

10 Claims. (Cl. 196—13)

This invention relates to the separation of mixtures of hydrocarbons by selective solvent action and more particularly to the solvent refining of mineral oils.

5 It is now well known that a large proportion of the mineral oils and gasolines of today are complex mixtures of paraffinic and non-paraffinic hydrocarbons. It is frequently desirable to separate the non-paraffinic hydrocarbons from the paraffinic hydrocarbons for various reasons. One of the main reasons is that the paraffinic hydrocarbons are in general more resistant to decomposition through heat and oxidation than the non-paraffinic hydrocarbons. Accordingly, 10 the oil containing the larger proportion of paraffinic constituents or, in other words, the relatively more paraffinic oils are more stable than the less paraffinic oils and hence are more desirable as lubricants and for other purposes.

20 Various methods have been proposed for separating the non-paraffinic from the paraffinic constituents of oils. One of the more common and oldest is by treatment with sulfuric acid which removes some of the non-paraffinic compounds from the oils. More recently it has been proposed to separate the non-paraffinic hydrocarbons by means of selective solvent extraction.

An object of the present invention is to provide a method for separating a mixture of paraffinic and non-paraffinic hydrocarbons into portions, one of which is relatively more paraffinic than the original mixture and the other relatively less paraffinic. Another object is the separation of relatively non-paraffinic bodies from mineral lubricating oils to produce lubricating oils of relatively high paraffinic character. A further object is the production of lubricating oils with improved viscosity-temperature curves from oils with poor viscosity-temperature curves. A still further object is to provide oils with improved resistance to oxidation and decomposition and to advance the art. Still other objects will appear hereinafter.

45 These objects may be accomplished in accordance with my invention by treating mixtures of paraffinic and non-paraffinic hydrocarbons with a furonitrile to remove the non-paraffinic hydrocarbons by the selective action of the furonitrile. By the term "a furonitrile" I mean furonitrile (C_4H_9OCN) and its homologues such as the methyl and ethyl furonitriles.

The oil is mixed with the furonitrile under such conditions that two layers are formed, one of which comprises the constituents which it is desired to extract from the oil, dissolved in the bulk of the liquid solvent, while the other comprises the undissolved and relatively paraffinic oil in admixture with a relatively small amount of the solvent. Preferably, my method comprises mixing the furonitrile with the hydrocarbon mix-

ture in approximately equal volumes and heating with agitation to a temperature at which the solvent and oil become substantially completely miscible. This solution is then cooled with agitation to a temperature approximately 20° C. below the temperature of complete miscibility, allowing the mixture to stand until separation into two layers occurs, separating the layers and removing the furonitrile from each layer. The furonitrile may be separated from the hydrocarbons by distillation. The residue, from the layer containing the larger amount of solvent consists of a large proportion of non-paraffinic and undesirable constituents. The residue, from the layer containing the smaller amount of solvent, consists primarily of the desirable paraffinic hydrocarbons.

In the examples given below the selective removal of non-paraffinic constituents from a mineral oil has been measured by following the 20 change in viscosity-gravity constant of the oil and by determining the change in viscosity index. The viscosity-gravity constant and its determination has been described by J. B. Hill and H. B. Coates in Industrial and Engineering Chemistry, 25 vol. 20, page 641, et seq., in an article entitled "The Viscosity-Gravity Constant of Petroleum Lubricating Oils." Fractions of a paraffinic character have lower constants than fractions of a naphthenic character. Viscosity index and its 30 calculation has been described by Dean and Davis in Chemical and Metallurgical Engineering, vol. 36, page 618. This index serves as a measure of the flatness of the viscosity-temperature curve of an oil. High values of the index are shown by 35 oils which are primarily paraffinic in character.

Example 1

A lubricating oil distillate (with the following characteristics: viscosity at 100° F., 566 sec. 40 Saybolt Universal; specific gravity at 60° F./60° F. 0.927; viscosity-gravity constant, 0.872) was mixed with an equal volume of furonitrile, heated with agitation to 40° C. at which temperature solvent and oil were miscible. The solution was 45 cooled to 10° C., while agitating, allowed to settle one-half hour, and the two layers withdrawn into separate containers. Furonitrile was removed from both layers under reduced pressure. The top layer was found to contain 69% of the volume 50 of the original oil. This oil had the following characteristics: viscosity at 100° F., 435 sec.; at 210° F., 55.5 sec; specific gravity at 60° F./60° F., 0.9053; viscosity-gravity constant, 0.844; viscosity index, 67.

Example 2

The lubricating distillate was treated as in Example 1 with the exception that the separation temperature was 20° C. Oil recovered from the 60

top layer was 64% of the volume of the original oil and possessed the following characteristics: viscosity at 100° F., 422 sec.; at 210° F., 55 sec.; specific gravity at 60° F./60° F., 0.9029; viscosity-gravity constant, 0.843; viscosity index, 67.

The conditions of application of the solvent will vary with the nature of the oil. Highly naphthenic oils will, in general, require a lower temperature to effect separation than highly paraffinic oils. The temperatures employed will, in general, range from about 0° C. to about 200° C. At the higher temperatures, it may be necessary to employ pressure to prevent substantial vaporization of the solvent. The ratio of solvent to oil may be varied within rather wide limits and will depend largely upon the nature of the oil being treated, the amount of non-paraffinic constituents therein and the quality of the refined oil desired. In general, the ratio of solvent to oil will lie between 1 to 10 and 5 to 1 parts by volume.

The application of the furonitriles as selective solvents is not confined to lubricating oil distillates. They may be employed to refine other hydrocarbon or mineral oil fractions such as cracked naphthas, gasoline, or kerosene fractions, whose boiling ranges are sufficiently different from the solvent to permit separation of the furonitrile. The furonitrile as employed need not be pure but may be included in mixtures, particularly mixtures of other solvents. Extraction treatment with the furonitrile may be applied to a raw distillate or to a partially refined product. Under certain conditions, for example in the case of oils with high sulfur content or poor sludging characteristics it may be desirable to supplement the furonitrile extraction with the usual acid, alkali, doctor, or clay treatment applied either before or after the solvent extraction.

While I have disclosed the preferred embodiments of my invention and the preferred modes of carrying the same into effect, it will be readily apparent to those skilled in the art that many variations and modifications may be made therein without departing from the spirit of my invention. Accordingly, the scope of my invention is to be limited solely by the appended claims construed as broadly as is permissible in view of the prior art.

I claim:

1. The method of treating a normally liquid hydrocarbon mixture containing relatively paraffinic and relatively non-paraffinic compounds which comprises extracting the hydrocarbon mixture with a furonitrile to separate the relatively non-paraffinic compounds from the relatively paraffinic compounds.

2. The method of treating a normally liquid hydrocarbon mixture containing relatively paraffinic and relatively non-paraffinic compounds which comprises mixing a furonitrile with the hydrocarbon mixture, causing the resulting mixture to separate into two layers and separating the layers, whereby the relatively non-paraffinic compounds are separated from the relatively paraffinic compounds.

3. The method of treating a normally liquid hydrocarbon mixture containing relatively paraffinic and relatively non-paraffinic compounds which comprises mixing a furonitrile with the hydrocarbon mixture, heating the resulting mix-

ture to a temperature where the furonitrile becomes completely miscible with the hydrocarbon mixture, cooling to about 20° C. below the temperature of complete miscibility and causing the mixture to separate into two layers, separating the two layers, and removing the furonitrile from each layer, whereby the relatively non-paraffinic compounds are separated from the relatively paraffinic compounds.

4. The method of treating a normally liquid hydrocarbon mixture containing relatively paraffinic and relatively non-paraffinic compounds which comprises extracting the hydrocarbon mixture with furonitrile to separate the relatively non-paraffinic compounds from the relatively paraffinic compounds.

5. The method of treating a normally liquid hydrocarbon mixture containing relatively paraffinic and relatively non-paraffinic compounds which comprises mixing furonitrile with the hydrocarbon mixture, causing the resulting mixture to separate into two layers and separating the layers, whereby the relatively non-paraffinic compounds are separated from the relatively paraffinic compounds.

6. The method of treating a normally liquid hydrocarbon mixture containing relatively paraffinic and relatively non-paraffinic compounds which comprises mixing furonitrile with the hydrocarbon mixture, heating the resulting mixture to a temperature where the furonitrile becomes completely miscible with the hydrocarbon mixture, cooling to about 20° C. below the temperature of complete miscibility and causing the mixture to separate into two layers, separating the two layers, and removing the furonitrile from each layer, whereby the relatively non-paraffinic compounds are separated from the relatively paraffinic compounds.

7. The method of refining mineral oil containing naphthenic and paraffinic constituents to separate the oil into fractions respectively rich in these constituents comprising mixing the oil with pyro-muconitrile, forming an extract phase containing naphthenic constituents dissolved in the solvent and a raffinate phase comprising relatively paraffinic constituents of the oil, separating the two phases, and removing the solvent liquid therefrom.

8. In the art of refining mineral oils, the process which comprises separating an oil containing paraffinic and naphthenic hydrocarbons into fractions respectively richer in paraffinic and naphthenic compounds by extracting said oil with a nitrile of furane.

9. The method of treating a normally liquid hydrocarbon mixture containing relatively paraffinic and relatively non-paraffinic compounds which comprises extracting the hydrocarbon mixture with methyl furonitrile to separate the relatively non-paraffinic compounds from the relatively paraffinic compounds.

10. The method of treating a normally liquid hydrocarbon mixture containing relatively paraffinic and relatively non-paraffinic compounds which comprises extracting the hydrocarbon mixture with ethyl furonitrile to separate the relatively non-paraffinic compounds from the relatively paraffinic compounds.

MELVIN A. DIETRICH. 70
